HOLDER FOR A PAIR OF SPECTACLES, STATIONERY ARTICLES OR THE LIKEPeter M. Herrema, 427 N. Rampart Blvd.,
Los Angeles, Calif.*Filed Oct. 13, 1959, Ser. No. 57,923*Term of patent 7 years*(Cl. D57—1)Fig. 1Fig. 2Fig. 4Fig. 3

Fig. 1 is a side elevational view of a holder for a pair of spectacles, stationery articles or the like, showing my new design;

Fig. 2 is a front elevational view;

Fig. 3 is a rear elevational view; and

Fig. 4 is a plan view.

The side opposite to that shown in Fig. 1 is the same as the side illustrated.

I claim:

The ornamental design for a holder for a pair of spectacles, stationery articles or the like, substantially as shown and described.
